UNITED STATES PATENT OFFICE.

LAWRENCE C. MOONEY, OF MONTGOMERY, ALABAMA.

CROSS-TIE.

1,016,845.

Specification of Letters Patent.

Patented Feb. 6, 1912.

Application filed June 1, 1911. Serial No. 630,714.

To all whom it may concern:

Be it known that I, LAWRENCE C. MOONEY, a citizen of the United States, residing at Montgomery, in the county of Montgomery and State of Alabama, have invented new and useful Improvements in Cross-Ties, of which the following is a specification.

This invention relates to railroad cross-ties and is designed to be relatively less expensive and more practicable than cross-ties now in common use.

To this end the invention comprises a cross-tie made principally of cement concrete and strengthened by a longitudinal bar of metal embedded therein and extending nearly from end to end, said bar having an enlarged portion near each end as high and as wide as the cross-tie to serve as supports for the rails. Within the enlarged portions are horizontal chambers or pockets open at one end only to receive blocks of wood or other suitable material capable of holding the rail spikes which are driven thereto through holes formed in the top of said enlarged portions. As the enlarged portions or pockets have the same height and width as the cross-tie they are not covered with the concrete forming the body of the tie, but separate the same into three sections, one section filling the space between the pockets, and a section extending from each pocket to the end of the cross-tie. The strengthening bar extends between the pockets and from each pocket toward the ends of the tie and serves to bind the concrete sections to the metal pockets or enlarged portions and thereby form a strong, rigid and time resisting structure.

In order to fully understand the invention, reference may be had to the accompanying drawings forming a part of this specification, in which—

Figure 1 is a plan view of the cross-tie. Fig. 2 is a vertical longitudinal sectional view taken on the line 2—2 of Fig. 1. Fig. 3 is a perspective view of the strengthening or reinforcing member, Fig. 4 is a vertical transverse sectional view on the line 4—4 of Fig. 1, enlarged. Fig. 5 is a horizontal sectional view, the left half being taken partially in the plane of the line c and the right half of the line d of Fig. 2. Fig. 6 is a view of a modification of a strengthening or rein-

forcing member. Fig. 7 is a side elevation of the improved tie having curved upper and lower faces.

Like reference characters are used to indicate the same parts in all the figures.

In the drawings, the numeral 1 indicates a strengthening member made of metal in the form of a flat horizontal plate, near each end of which is an enlarged portion 2 projecting above and below the faces of the plate and laterally beyond its edges. These enlarged portions 2 are made hollow to form horizontal chambers or pockets 3 open at one end, as shown in Figs. 3 and 4, into which pockets or chambers are inserted blocks 4 of wood or other suitable material capable of holding rail spikes when driven thereto. These blocks preferably fill the pockets 3 and contact on all sides with the walls thereof, the blocks in fact being driven into the pockets so as to fit tightly therein. The top of the enlarged portions 2 serve as bearings for the rails which are secured thereon by spikes driven through holes 5 formed in the top wall of the pockets into the wooden blocks 4. The rails are held to proper gage by means of flanges or overhanging lips 2^a projecting upwardly from the top of the portions 2 under which one edge of the base flange of the rails is inserted. Small ribs 2^b, spaced from the lips 2^a engage with the opposite edges of the base flanges and prevent the rails from rising and moving laterally from beneath the lips 2^a. These lips and ribs assist the spikes to hold the rails and relieves said spikes from a portion of the strain and resistance to which they are ordinarily subjected. The ends 1^c of the strengthening member project a short distance from the enlarged portions 2 toward the ends of the tie and are preferably formed with lateral flanges or T-shaped heads 6, as shown in the drawings, for the purpose of binding and anchoring the concrete forming the tie ends closely to said member.

Perforations 7 are formed in the enlarged portions or pockets 2 near the top and bottom walls of the same and transversely thereof, but longitudinally of the tie, in which perforations are seated camber rods 8 extending from one pocket 2 to the other and fastened in position by means of nuts

9 screwed on the ends of said rods against the sides of the pockets or, when the pockets incline as in the drawings, against lugs 10. The number of camber rods may vary according to requirements, two being shown on the upper side of the tie and two on the lower side in the present construction. Other strengthening rods 11 extend longitudinally of the tie from near one end to the other. These rods pass through perforations 12 parallel with the perforations 7 in the top and bottom walls of the pockets but are not fastened thereto. Their ends are by preference bent upon themselves to form hooks or loops 13.

The strengthening member 1 with its camber rods 8 and tie rods 11 are placed in a suitable mold, and the latter filled with a concrete cement which is packed around the central web of the strengthening member and the tie rods 8 and 11. Openings 22 may be formed in the web of the member 1 to be filled with concrete for more firmly binding together the concrete on opposite sides. These openings, however, may be omitted. After the material has hardened the tie is removed from the mold and presents the appearance shown in the drawings, the top and ends of the enlarged portions or pockets being exposed and flush with the respective parts of the cross-tie. Below the enlarged portions or pockets 2 there is a layer of concrete 15^a which serves to strengthen the tie and bind together the sections of concrete on opposite sides of each pocket. This additional layer of concrete may, however, be omitted, as shown in Fig. 7, thus exposing the bottoms of the portions or pockets 2. By this construction the concrete structure of the tie is divided into three sections, 15, 16 and 17, the section 15 extending between the pockets 2 and sections 16 and 17 from the pockets to the ends of the tie. Said ends are preferably finished by a layer of cement 18. The cross-tie is preferably, though not necessarily, made wider and thicker in the middle than at its ends, and as represented in the drawings, the sides of the tie taper gradually from the center toward each end while the top and bottom of the tie may be parallel as in Fig. 2, convexly curved between the pockets and parallel from the pockets to the ends, as in Fig. 7, or even of less width at the center than at the ends.

The strengthening member including the central web, the enlarged portions or pockets 2, and the end portions 1^a may be and preferably are an integral casting of iron or steel, but it may be made in sections, as shown in Fig. 6, wherein the central web 19 is a separate casting having end flanges which are bolted as shown to the pockets 2, each of which is also a separate casting.

The enlarged portions or pockets 2 are

preferably made of substantially hexagonal shape as represented in the drawings, to provide the slight amount of resiliency found necessary in all cross-ties to prevent the destruction of the rails and rolling stock, which results when a perfectly rigid rail support is employed. To prevent the blocks being driven through the pockets and to limit the surface of the blocks exposed to the elements, one end of each pocket is closed by a wall 20 having a small aperture 21 into which may be inserted any suitable tool for driving out the block when the latter is to be replaced by a new block.

Having thus described the invention what is claimed as new is:—

1. A composition tie, comprising a concrete body having a metallic strengthening member embedded therein, said member having pockets formed at the ends thereof, and cushion blocks in said pockets surrounded on all sides by the walls of said pockets, one of the walls of each pocket constituting a bearing for a rail.

2. A composition tie, comprising a concrete body having a metallic strengthening member embedded therein, said member having pockets formed at the ends thereof, cushion blocks in said pockets surrounded on all sides by the walls of said pockets, one of the walls of each pocket constituting a bearing for a rail, and tie rods extending between said pockets.

3. A composition tie, comprising a concrete body having a metallic strengthening member embedded therein, said member provided with pockets at the ends thereof and integral therewith, and cushioning blocks in said pockets surrounded on all sides by the walls of said pockets, one of the walls of each pocket constituting a bearing for a rail.

4. A composition tie, comprising a concrete body having a metallic strengthening member embedded therein, said member provided with pockets adjacent the ends thereof, and cushion blocks in said pockets surrounded on all sides and one end by the walls of said pockets, one of the walls of each pocket constituting a bearing for a rail.

5. A composition tie, comprising a concrete body, having a metallic strengthening member embedded therein, said member having pockets formed adjacent the ends thereof and integral therewith, and cushion blocks in said pockets surrounded on all sides and one end by the walls of said pockets, one of the walls of each pocket constituting a bearing for a rail.

6. A composition tie formed of a plurality of concrete sections and interposed metal sections, and a metal strengthening member integral with the metal sections, embedded in the concrete sections of said body for binding the same together.

7. A composition tie, comprising a concrete body having metallic rail supporting members embedded in and adjacent the ends thereof, said members having pockets formed therein, and cushion blocks in said pockets surrounded on all sides by the walls of said pockets, one of the walls of each pocket constituting a bearing for a rail. 70
8. A composition tie, comprising a concrete body having metallic rail supporting members embedded in and adjacent the ends thereof, said members having pockets formed therein, cushion blocks in said pockets surrounded on all sides by the walls of said pockets, one of the walls of each pocket constituting a bearing for a rail, and a metallic web connecting said pockets. 75
9. A composition tie, comprising a concrete body having metallic rail supporting members embedded in and adjacent the ends thereof, said members having pockets formed therein, cushion blocks in said pockets surrounded on all sides by the walls of said pockets, one of the walls of each pocket constituting a bearing for a rail, and a metallic web connecting said members and integral therewith. 80
10. A composition tie, comprising a concrete body having a metallic strengthening member embedded therein, said member having pockets formed therewith near the ends thereof, and cushion blocks in said pockets surrounded on all but one side by the walls of said pockets, one of the walls of each pocket constituting a bearing for the rail, said walls having apertures therein for the rail fastening spikes. 85
11. A composition tie, comprising a concrete body having a metallic strengthening member embedded therein, said member having pockets formed therewith near the ends thereof, cushion blocks in said pockets, the walls thereof surrounding said blocks on all sides and one end, one of said pocket walls constituting a bearing for the rail, the closed end of each pocket being provided with an aperture through which to pass a block expelling tool. 90
12. A composition tie, comprising a body having a central section and two end sections of concrete, metal rail supporting members between the sections, a metallic strengthening member embedded in said central section and connecting the rail supporting members, and a projection on each rail supporting member embedded in the adjacent end section. 95
13. A composition tie, comprising a body, said body composed of a central section and two end sections of concrete, a metallic strengthening member embedded in said central section and provided with pockets at the opposite ends thereof between said concrete sections, cushion blocks in said pockets surrounded on all sides and one end by the walls of said pockets, one of the walls of each pocket constituting a bearing for a rail. 100
14. A concrete tie, comprising a body having a metallic strengthening member embedded therein, said member having pockets formed near the ends thereof, the top and bottom walls of which are transversely perforated, longitudinal rods extending between said pockets and seated in said perforations, and cushion blocks tightly fitted in said pockets the top walls of said pockets constituting bearings for the rails. 105
15. A concrete tie, comprising a body having a metallic strengthening member embedded therein and provided with pockets formed near the ends thereof, said pockets being flush with the sides of the tie and having transverse perforations in their upper and lower faces, rods extending longitudinally of the tie between the pockets seated in said perforations and fastened to said pockets, other longitudinal rods having bent ends extending from end to end of the tie, also seated in perforations in said pockets, and a cushion block in each pocket surrounded on all sides and one end by the walls of the pocket, one of said walls serving as a bearing for a rail. 110
16. A concrete tie, comprising a body having a metallic strengthening member and tie rods embedded therein, said member having pockets formed near the ends thereof with perforations to receive said rods, and a cushion block in each of said pockets closely fitting the walls of the same, one of which walls serves as a bearing for a rail. 115
17. A composition tie, comprising a body formed of a central section and two end sections of concrete, a metallic strengthening member and tie rods embedded in said central section, a rail supporting member integral with the strengthening member disposed between the central concrete section and each end section, said rail supporting members having pockets therein open at one end only, their opposite ends being closed by a wall having an aperture therein, cushion blocks fitted into said pockets, and projections on the outer sides of the rail supporting member embedded in the concrete end sections of the tie. 120
18. A composition tie comprising a body formed of a central section and two end sections of concrete, a metallic strengthening member and tie rods embedded in said central section, a rail supporting member integral with the strengthening member disposed between the central concrete section and each end section, said rail supporting members having pockets therein opened at one end only, their opposite ends being closed by a wall having an aperture therein, 125
- 65

an overhanging lip and a rib parallel thereto projecting from the rail supporting surface of each pocket for engaging the rails, cushioning blocks fitted into said pockets, 5 and projections on the outer side of the rail supporting members embedded in the end concrete sections of the tie.

In testimony whereof I have hereunto set my hand in presence of two subscribing witnesses.
